UNITED STATES PATENT OFFICE

JAMES EDGAR LEE, FREEMAN BARNEY, AND PHILIP J. BEATTY, OF GRAND HAVEN, MICHIGAN, ASSIGNORS TO CHALLENGE MACHINERY COMPANY, OF GRAND HAVEN, MICHIGAN, A CORPORATION OF MICHIGAN

THREE-WAY CHASE LOCKUP

Application filed May 30, 1930. Serial No. 457,578.

This invention relates to a three-way chase locking device used by printers, which is of value in not only making a very rapid locking of set-ups of type or their equivalent in a printer's chase, but is of utility to compensate for various minor discrepancies in dimensions of set-ups, a number of them, which may be located in a chase so that each of the set-ups is in effect individually acted upon by the locking mechanism and none of the set-ups will be loose while others are properly locked in position.

In the present invention the type or other set-ups which are used are of substantially uniform size, and a number of them, four usually though the number may be increased or diminished, may be located in the chase and with our locking mechanism the same may be independently acted upon at a side and at an end of the set-ups to securely hold the same in place. The invention is especially useful in connection with printing the pages of directories, such as telephone and other directories, though in no sense limited thereto; as books of any size having uniform sizes of pages may have set-ups alike as to size for the pages thereof and the chase locking apparatus of our invention is readily applicable thereto.

It is an object and purpose of the present invention to provide a chase locking apparatus whereby a rapid change of set-ups in the chase and locking of the new set-ups in place is attained with a surety that each of the set-ups located in the chase will be properly held. Many other objects and purposes will be apparent and may be understood from the following description of the invention taken in connection with the accompanying drawing, in which,

Fig. 1 is a plan view of a chase having a plurality of set-ups locked therein by use of our invention, and

Fig. 2 is a fragmentary enlarged plan illustrating the manner in which the locking mechanisms are operated by means of an operating key therefor.

Like reference characters refer to like parts in the figures of the drawing.

The printer's chase of conventional rec-

tangular shape and form is made of any suitable material. It has parallel spaced sides 1 and, likewise, parallel spaced ends 2. The chase ordinarily has a sheet metal bottom but the details of construction of the chase are not important in the present invention, and will not be specifically described herein.

Substantially mid-way between the ends of the chase and extending across the same is a dividing bar 3 connected at its outer ends to the chase sides and recessed at its center as shown. The set-ups 4 of type, cuts or the like are to be located with one side against the inner sides of the chase sides 1 and with one end of each against the sides of the bar 3; the inner sides of the set-ups 4 being spaced from each other.

In the spaces thus left between the set-ups 4 at their inner sides two bars 5 are located at each side of the division bars 3, one against the inner side of each of the set-ups 4. The opposite sides of the bars 5 are provided with wedging or locking projections 6, having inclined sides as shown, a plurality of the parts 6 being located lengthwise of each bar 5 in spaced relation thereon.

Between each of the pairs of the bars 5 a locking bar 7 is located of the shape shown, and which is provided with cooperating wedging surfaces 8 to engage with the wedging surfaces 6 on the bars 5 whereby, when the locking bars 7 are drawn in one direction, said bars 5 are forced away from each other against the inner sides of the set-ups 4 pressing the same very securely against the inner sides of the chase sides 1.

At the adjacent ends of each of the locking bars 7 a rack member 9 is secured. The racks extend by each other with the teeth of the racks facing each other. These rack bars 90 pass underneath plates 10 of metal which partly bridge the gap over the adjacent recess ends of the dividing bar 3 of the chase. The plates 10 have a space therebetween for the passage of an operating key 11, shown in cross section in Fig. 2, as in the shape of a four-toothed pinion, preferably, and engaging with both of the rack bars and operating the same simultaneously in opposite directions, whereby all of the set-ups 4 in a chase 100

may be tightened and locked at their sides by a single operation of the key 11 passing through the opening in the plate 10 and engaging with the racks 9.

- 5 The ends of the set-ups 4 opposite those bearing against the dividing bars 3 are spaced from the ends 2 of the chase, in which spaces two pairs of bars 15 with wedging projections 16 at their inner sides are located. 10 Locking bars 17 having cooperating wedging parts 18 thereon are located one between each pair of bars 15. The locking bars 17 likewise are provided with rack members 19 passing by each other and engageable by the same key 11 to reciprocate the same. Said rack bars 19 are guided at their free ends in suitable guides 20.
- 20 With this construction, with one operation of the key 11 to draw the bars 7 toward each other the chase set-ups are located at their sides, while with two additional operations, one at each end of the chase to operate the two pairs of locking bars 17, one pair being at each end of the chase, the ends of the set-ups are engaged and pressed into secure holding engagement with the dividing bar 3.
- 25

Such a construction compensates for minor discrepancies in the outer dimensions of the set-ups 4. We have heretofore filed an application for patent having Ser. No. 440,451 and filing date of March 31, 1930 in which all of the locking members, those extending lengthwise of the chase and those at the ends of the chase are simultaneously operable by one key operation. In some instances small discrepancies in the outer dimensions of the set-ups 4 cause some of the set-ups to be firmly locked and others to be less firmly locked either at a side or end but with the present invention this will not occur. With the present invention the quick and ready assembly or release of the set-ups may be had, as is very evident. Also, the present invention is advantageous over the application previously referred to as the set-ups 4 can be made longer, as less end space is required for the herewith disclosed three-way chase locking mechanism than was needed for the toggle arrangement formerly set forth. The invention is defined in the appended claims and is to be considered comprehensive of all forms of structure coming within their scope.

We claim:

- 55 1. In combination, a printer's chase, a plurality of set-ups located in the chase, each having one side bearing against a side of the chase, manually operable locking means located between the set-ups at their other sides, means to simultaneously force the set-ups into secure holding engagement with the sides of the chase, and other manually operable locking means located against ends of said set-ups to bear thereagainst and to simultaneously force the opposite ends of

the set-ups against and into secure holding engagement with a fixed part of said chase.

2. In combination, a printer's chase of rectangular form having sides and ends, a dividing bar extending between the sides substantially midway between the ends of the chase, four set-ups located in the chase each with one side against a side of the chase and one end against the dividing bar, manually operable locking means located between the remaining sides of the set-ups to force the same against the sides of the set-ups to force the same against the sides of the chase, and two additional independent locking means between the ends of the chase and the adjacent ends of said set-ups for forcing the same against the dividing bar.

3. A construction containing the elements in combination defined in claim 2, combined with a common means for individually and independently manually operating each of said locking means.

4. In combination, a rectangular printer's chase, a plurality of set-ups of rectangular form located in the chase, one end and one side of each of said set-ups bearing against relatively rigid and stationary parts of the chase, the opposite sides of said set-ups being spaced from each other and the opposite ends thereof being spaced from the ends of the chase, locking means located between said opposite sides of said set-ups, means for manually operating the same to spread the same apart against the adjacent sides of the set-ups, and similar locking means, one at each end of the chase between the same and the adjacent end of said set-ups and individually and independently manually operable by the same means used for operating the first locking means.

5. In combination with a rectangular printer's chase, a plurality of type set-ups of rectangular form each having a side and a transversely extending end located in said chase, manually operable clamping means simultaneously acting against the sides of three or more of said type set-ups and additional independently manually operable clamping means acting against the ends of a plurality of said type set-ups.

In testimony whereof we affix our signatures.

JAMES EDGAR LEE.
